UNITED STATES PATENT OFFICE.

ALBERT FROST, OF ST. LOUIS, MISSOURI.

FENCE.

No. 798 604.

Specification of Letters Patent.

Patented Sept. 5, 1905.

Application filed September 12, 1904. Serial No. 224,204.

To all whom it may concern:

Be it known that I, ALBERT FROST, a citizen of the United States, residing at St. Louis, State of Missouri, have invented certain new and useful Improvements in Fences, of which the following is a specification, reference being had therein to the accompanying drawing.

The object of my invention is to provide a metallic fence that is simple and inexpensive in construction.

My invention consists of a number of longitudinally-extending fence-wires that are supported in spaced parallelism by a framework made up of connected sections extending in the direction of the line of the fence, each section comprehending a pair of inverted-V-shaped braces that are secured at their apexes to provide four outwardly-spreading legs that are arranged in forwardly and rearwardly projecting pairs, that are connected at their respective extremities with those of the adjacent section.

In the accompanying drawing there is represented a view in perspective of a portion of a fence made in accordance with my invention.

In carrying out my invention I preferably employ strips of metal that for the purpose of description may be said to be V-shaped in cross-section to provide strengthening-flanges, and which are bent to form inverted-V-shaped braces 2, that terminate in right-angular-extending feet-clamping portions 3, that are each provided with bolt-holes 4. These metal strips are also provided at spaced intervals throughout their length with perforations or holes, the purpose of which will be presently explained. The sectional framework of the fence is made up of pairs of these inverted-V-shaped braces 2, crossed centrally in a manner to provide four outwardly-spreading legs that are arranged, respectively, in forwardly and rearwardly projecting leg pairs. These inverted-V-shaped braces are connected to each other at their point of crossing or apexes by a tie-wire 6, that is passed through the holes 5 and then twisted into a loop about the top longitudinally-extending fence-wire.

The framework of the fence is made up of a series of sections constructed in accordance with the above description, which are arranged in proximity to each other in alinement and which are secured together by uniting the overlapping feet of the adjacent leg pairs by the anchoring-bolts 7, that are passed, respectively, through the bolt-holes 4, formed in said feet. The bolts 7 are held in a vertical posi-

tion by a connecting anchor-plate 8, that extends laterally therefrom at its lower end and that is embedded in the ground, as shown. Each member is composed of two legs, one of which is adapted to support the wires, and when a series of these are used to make a fence each alternate one crosses the next one above—that is, take one member, the second one crosses over the first member, and the third member crosses the second one underneath, the fourth one over the third, and the fifth one underneath the fourth, &c. The terminating leg pairs of a fence thus constructed may be prevented from spreading and be securely anchored by the employment of a transversely-extending sustaining rod or bolt 9, that is passed through the hole 4 in one of the feet and that is of sufficient length to extend to and in connection with the feet of the opposite leg in a plane to be embedded in the ground to form thereby a suitable anchorage.

The longitudinal strands of fence-wire 10 are held in proper spaced parallelism against the front legs of the braces 2 by the tie-wires 11, that are threaded through the holes 5 and which are united, respectively, to the intersecting longitudinally-extending strand.

Having described my invention, what I claim is—

1. In a fence, the combination of a plurality of uniting sections, comprising each a pair of inverted-V-shaped braces crossed and united to each other at their apexes, to provide forwardly and rearwardly projecting leg pairs, and longitudinally-extending fence-wires arranged in spaced parallelism and supported by said sections, substantially as described.

2. In a fence, the combination of a plurality of sections, comprising each a pair of inverted-V-shaped braces crossed and united to each other at their apexes to provide forwardly and rearwardly projecting leg pairs, that terminate in right-angular-extending feet, bolts having anchor-plates for uniting, respectively, the contiguous feet of opposite adjacent leg pairs; and longitudinally-extending fence-wires arranged in spaced parallelism, that are supported and tied to said sections, substantially as described.

3. In a fence, the combination of a plurality of connected sections, comprising each a pair of inverted-V-shaped braces crossed and united to each other at their apexes to provide forwardly and rearwardly projecting leg pairs, the terminal legs of said fence being anchored by a transversely-extending embedded rod;

and longitudinally-extending fence-wires arranged in spaced parallelism and supported by said sections, substantially as described.

4. A postless fence comprising longitudinal wire members and a supporting-frame secured thereto composed of inverted-V-shaped members alternately crossing each other and having their ends anchored to the ground.
5. A wire-fence support comprising inverted-V-shaped members having alternate legs engaging the ground and supporting the wires.

6. A wire-fence support comprising inverted - V - shaped members alternately crossing each other and having each alternate leg supporting the wires, and means joining said members and anchoring them to the ground. 15

In testimony whereof I affix my signature in presence of two witnesses.

ALBERT FROST.
